UNITED STATES PATENT OFFICE.

FRANK L. ANTISELL, OF PERTH AMBOY, NEW JERSEY.

CENTRIFUGAL PUMP.

1,281,478.

Specification of Letters Patent. Patented Oct. 15, 1918.

Application filed August 24, 1917. Serial No. 187,978.

To all whom it may concern:

Be it known that I, FRANK LINDEN ANTISELL, a citizen of the United States, and a resident of Perth Amboy, county of Middlesex, State of New Jersey, have invented certain new and useful Improvements in Centrifugal Pumps, of which the following is a specification.

This invention relates to centrifugal pumps and more particularly to centrifugal pumps for handling corrosive and erosive solutions.

One of the more important objects of the invention is to provide a pump characterized by an initially high mechanical efficiency and the ease with which said efficiency may be maintained. Another of the more important objects is to simplify the construction and to so correlate the parts that the pump may readily be assembled and taken apart.

The accompanying drawings illustrate preferred embodiments for carrying into practice the foregoing objects and others which will be apparent to those familiar with the invention and the art to which it appertains. It will be understood that the illustrated forms are merely exemplary and that while I shall describe the same with some degree of particularity I nevertheless wish it understood that changes in the details may be made without departing from the spirit of the invention or the scope of the subjoined claims.

In said drawings, wherein like characters of reference denote corresponding parts in the several views:—

Figure 1 is a view partly in elevation and partly in vertical section of a centrifugal pump embodying the present improvements. Fig. 2 is a detail view of one desirable form of rotary part, showing the same partly in plan and partly in section.

Fig. 3 is a vertical section on the line 3—3 of Fig. 2.

Fig. 4 is a detail view in vertical section, of a part of the casing and certain other stationary parts of the pump, correlated to receive rotary members or impellers between them.

Fig. 5 is a plan view of one of the parts shown in Fig. 4; and

Fig. 6 is a detail sectional view of a slightly modified form of rotary members or impellers.

The present invention is preferably embodied in a centrifugal pump of a multi-

stage type and I have illustrated and will hereinafter describe in detail an advantageous construction and correlation of parts in a pump of this type. It further preferably is embodied in, and will be described with reference to, a pump of the vertical type but this also may be varied.

A designates a suitable supporting member mounted upon an appropriate base B and having spaced arms or brackets C, C', with aligned openings. These openings are provided with suitable bearings c c' through which the impeller shaft D extends. This shaft is suspended from the upper arm or bracket C and is adjustable longitudinally.

E designates the casing of a multi-stage vertical pump. This casing is disposed below the arm or bracket C' and is preferably mounted on the base B. The casing is provided with an inlet e and an outlet e' and between these there is an inclined wall forming a ledge e² and also forming a tapered throat leading to a portion of the casing which is expanded to form a chamber E' 80 which extends around the casing and is open along its inner wall. The outlet e' extends from this chamber. F designates a stationary member which constitutes a cover and has a body portion f and a peripheral flange 85 f', which flange rests on the ledge e² of the casing. This cover is held in position, preferably by a suitable number of threaded rods G which extend through the top e³ of the casing and are provided with nuts g, g, above 90 and below said top.

H H' designate removable sections of a stationary member which constitutes a sectional diaphragm. This diaphragm is mounted upon the wall e² below the cover F 95 and extends thence into the casing. It will be noted that the correlation of the parts is such that a chamber F' is formed by the cover F and diaphragm-sections H H' and that said diaphragm-sections separate the 100 chamber E' from the chamber F'.

Suitably fixed to the lower end of the shaft D, in this particular exemplification of the invention, are rotary members constituting two impellers I, I', formed with 105 vanes i i'. These impellers operate in the chambers E' and F', respectively. They are preferably formed integral with a sleeve I² into which the shaft D extends and they are preferably secured to the shaft by the key i². Each impeller has a plurality of vanes and these vanes are of arcuate shape 110

- and have their inner ends spaced from the axial center of the impellers. It will be noted that the portion f of the cover and the diaphragm sections H , H' are formed 5 with openings at the vertical axis of the pump and that these openings are of greater diameter than the portions of the impellers contiguous thereto, respectively, thus providing spaces i^3 and i^4 at the axis of the 10 pump through which the liquid may flow. It will also be noted that the impeller I' is of less diameter than the chamber F' thus providing a space between its periphery and the walls of said chamber. The vanes i' of 15 the impeller I' preferably extend from the outer edge of the impeller to the space d^3 and preferably have their upper edges substantially in contact with the under surface of the portion f of the cover, so as to constitute a seal. The vanes i similarly preferably extend from the periphery of the impeller I to the space i^4 and preferably have their upper edges substantially in contact with the under surface of the diaphragm 20 sections H , H' , to constitute a seal. These diaphragm-sections have their upper surfaces provided with a plurality of vanes h and h' extending toward but not essentially in contact with the under surface of the impeller I' ; and the portion f of the cover similarly has a plurality of vanes f^2 which project upwardly therefrom. The vanes f^2 preferably extend to the space i^3 and the vanes h , h' preferably extend to the space i^4 . 25 30 35 It will thus be seen, in the operation of the pump herein exemplified, that the liquid which is usually of a corrosive or erosive nature will flow from the inlet e gravitally to the space i^3 , through a series of channels 40 separated from each other by the vanes f^2 , and that said vanes act to stop the rotation of the liquid due to the rotation of the shaft D . The liquid flows through the axial opening in the cover and into the space i^3 and thence is forced by the rotating impeller I' with its vanes i' into that portion of the chamber F' lying between the periphery of the impeller I' and the flange f' of the cover F . The movement imparted to the liquid 45 by the impeller I' causes it to whirl, as is evident. It then flows between the stationary vanes h , which retard or stop its rotative movement and passes within the space i^4 and around the inner edge of the diaphragm sections H , H' , where it comes under the influence of the impeller I with its vanes i , where it is again given a swirling motion 50 and is forcibly impelled to the chamber E and thence through the outlet e' . 55 60 X is a point representing the greatest bending moment for loads applied laterally to the impeller, and is situated below the lower edge of the bearing C' . Attention is called to the fact that the portion f of

the cover, the impellers I and I' and the diaphragm-sections H , H' have confronting surfaces which are curved on an arc struck from said point X . In other words these parts of the pump are developed in a spherical form upon the point of greatest bending moment of the shaft. Important advantages result from this correlation of parts for the reason that it allows for the unavoidable vibration of the rotating members and makes it practicable to provide a minimum 70 of clearance between the impellers and the contiguous surfaces of the cover and diaphragm-sections. Moreover, the necessity for the provision of sealing rings which must be frequently renewed in pumps 75 hitherto proposed, however carefully the rotating members thereof are balanced, is avoided and, likewise, there is avoided the excessive wear to which the packing rings or impellers that are center hung with their 80 bearings close together have hitherto been subjected. 85

Again, it will be noted that during the passage of the liquid from the upper to the lower surface of the upper impeller. Heretofore a great deal of attention has been given to providing a passage-way between the cover and the successive stages of the pump with a view of eliminating what may 90 be termed a counter centrifugal force. I have found that such construction is not desirable as the drag between the impeller and the wall lowers the efficiency to a much greater extent than the construction herein exemplified. 95 100

Among the other advantages, I have also found that I am able to use a much smaller shaft for a given overhang than it would be possible to use if it were necessary to keep 105 the running parts in close enough contact to obtain a satisfactory initial efficiency which decreases the frictional resistance of the pump bearings.

In short it will be noted that the correlation of parts herein exemplified results in a pump which combines the advantages of a high initial efficiency with simplicity of construction. It will also be apparent that the efficiency of the pump may be maintained by proper adjustment of the impellers with their vanes. As hereinbefore stated the shaft D is adjustable longitudinally through the bearings c and c' and is maintained in position by the nuts J and J' . Its upper 110 end is formed with three sections marked d , d' and d'' respectively. The section d' is of less diameter than the section d and the section d'' is of less diameter than the section d' . The bearing c is mounted upon 115 the section d' and its lower end rests partly upon the shoulder d^2 formed at the junction of the sections d and d' respectively and 120 125

partly upon the upper end of the nut J. The nut J' is above the bearing c and is threaded upon the section d'' and its lower end bears upon the upper surface of the bearing c, and 5 partly upon a shoulder d³ formed at the junction of the sections d' and d'' and partly upon the upper surface of the arm or bracket C. This correlation of parts obviously is one which enables them to be 10 readily assembled, and also readily affords access to the bearing when the latter should be renewed, as well as affording means for the convenient adjustment of the shaft with the impellers. To more effectively maintain the parts in adjusted position, I prefer 15 to employ lock nuts j² and j³ below and above the nuts J and J' respectively.

It is believed that the construction, operation and advantages of the invention will 20 be comprehended from the foregoing description and appended drawings of the preferred embodiment thereof, and that it will be understood that the description and drawings are intended to set forth and illustrate merely a preferred embodiment and that the invention may be otherwise embodied as to details without departing from its spirit or the scope of the claims. Particularly should it be understood that while 25 I have illustrated a pump having two impellers, certain essential features of the invention may be embodied in a pump having only one impeller, or in a pump having more than two impellers.

Again it will be understood that while 30 thus far I have illustrated and described the impellers as having vanes in the shape of plates whose upper edges are substantially in contact throughout their lengths with the 35 undersurface of the stationary members f and H, H', the benefits arising from vanes thus related to the stationary parts may be secured by providing each rotary member or impeller with a plate or cover which extends over the body of the same and is spaced from said body and is connected therewith at intervals by ribs; as illustrated in Fig. 6 in which N N' designate the covers. In such case it is preferred to provide 40 the covers with thickened portions n, n' which will contact with the adjacent stationary members respectively and form seals at these places, the remaining portions of the impellers being out of contact with the 45 stationary members and thus reducing friction. Obviously the ribs which have been referred to form vanes by which the liquid is impelled with a whirling motion.

Having now described the invention what 50 I believe to be new and desire to secure by Letters-Patent is:—

1. A centrifugal pump comprising a shaft, a rotary member carried thereby and a stationary member, said stationary and ro-

tary members having their confronting and 65 engaging surfaces developed in a spherical form upon a radius from the point of greatest bending moment of the shaft.

2. A centrifugal pump comprising a shaft, a casing having an inlet and an outlet 70 and provided with a plurality of communicating chambers between the inlet and the outlet, and a plurality of impellers secured to the shaft and operating in said chambers, respectively, said impellers and chambers 75 having confronting surfaces developed in a spherical form struck upon a radius from the point of greatest bending moment of the shaft.

3. A centrifugal pump comprising a 80 shaft, a casing having an inlet and an outlet and also having a cover and a diaphragm correlated to provide a plurality of communicating chambers between the inlet and the outlet, and a plurality of impellers secured to the shaft and operating in said chambers, respectively, said cover, impellers and diaphragm having their surfaces developed in a spherical form struck upon a radius from the point of greatest bending 85 moment of the shaft.

4. A centrifugal pump comprising a casting having an inlet and an outlet and provided with a ledge wall between the same, a diaphragm whose peripheral portion rests 90 upon the said ledge wall, a cover having a peripheral flange which also rests upon the said ledge wall and holds the diaphragm removably in place, and an impeller in operative relation with the diaphragm.

5. A centrifugal pump comprising a shaft, a casing having an inlet and an outlet, and provided with a ledge between the same, a diaphragm whose peripheral portion rests upon the said ledge, a cover having a peripheral flange which also rests upon the said ledge and holds the diaphragm removably in place, said cover and diaphragm providing a plurality of communicating chambers between the inlet and the outlet, and a plurality of impellers secured to the shaft 105 and operating in said chambers, respectively.

6. A centrifugal pump comprising a shaft, a casing having an inlet and an outlet 115 and provided between the same with a removable sectional diaphragm and a cover which holds the diaphragm in place, said cover and diaphragm providing a plurality of communicating chambers within the casting, and a plurality of impellers secured to the shaft and operating in the chambers, respectively, said cover, diaphragm and impellers having surfaces developed in a spherical form struck upon a radius from 120 the point of greatest bending moment of the shaft.

7. A centrifugal pump comprising a ro-

tary shaft, an impeller carried thereby, and a stationary member operatively related to the impeller and having vanes to reduce the rotation of the liquid pumped, said impeller and stationary member having confronting surfaces developed in a spherical form struck upon a radius from the point of greatest bending moment of the shaft.

8. A centrifugal pump comprising a rotary shaft, a casing having an inlet and an outlet and provided between the same with a plurality of stationary members correlated to form a plurality of communicating chambers, said members having vanes, and a plurality of impellers secured to the shaft and operating in said chambers respectively, said impellers and stationary members having surfaces developed in a spherical form struck upon a radius from the point of greatest bending moment of the shaft.

9. A centrifugal pump, comprising a rotary shaft, a casing having an inlet and an outlet and provided between the same with a removable sectional stationary member having vanes, means for holding the stationary member in place, and an impeller secured to the shaft and operatively related to the stationary member, said impeller and stationary member having confronting surfaces developed in a spherical form struck upon a radius from the point of greatest bending moment of the shaft.

10. A centrifugal pump comprising a rotary shaft, an impeller carried thereby and provided with vanes, and a stationary member operatively related to the impeller, said stationary member and impeller vanes having confronting portions curved upon an arc struck from the point of greatest bending moment of the shaft.

11. A centrifugal pump comprising a rotary shaft, an impeller carried thereby, and a stationary member, said impeller having

means which are substantially in contact with the stationary member to constitute a seal and said stationary member and impeller having confronting portions which are curved upon an arc struck from the point of greatest bending moment of the shaft.

12. A centrifugal pump comprising a rotary shaft, an impeller carried thereby, a stationary member, said impeller having means which are substantially in contact with the stationary member to constitute a seal, the contacting portions being curved upon an arc struck from the point of greatest bending moment of the shaft.

13. A centrifugal pump comprising a rotary shaft, an impeller carried thereby and including vanes and with a cover for the vanes, and a stationary member, the cover of the impeller having projections in contact with the stationary member to constitute a seal the confronting surfaces of which are curved upon an arc struck from the point of greatest bending moment of the shaft.

14. A centrifugal pump comprising a rotary longitudinally adjustable shaft having means for fixing it in adjusted position, an impeller carried thereby, and a stationary member in operative relation with the impeller, said impeller and stationary member having confronting and engaging surfaces which are curved upon an arc struck from the point of greatest bending moment of the shaft.

In witness whereof I have hereunto set my hand at Perth Amboy, County of Middlesex, State of New Jersey, this 20 day of August, 1917.

FRANK L. ANTISELL.
